MEANS FOR CONTROLLING THE FEED OF OIL AND STEAM IN THE MANUFACTURE OF GAS.

No. 926,628.

Specification of Letters Patent.

Patented June 29, 1909.

Application filed December 21, 1907. Serial No. 407,556.

To all whom it may concern:

Be it known that I, FREDERICK H. WAGNER, a citizen of the United States, residing at Baltimore, in the State of Maryland, have 5 invented certain new and useful Improvements in Means for Controlling the Feed of Oil and Steam in the Manufacture of Gas, of which the following is a specification.

This invention relates to improvements in 10 means for feeding oil to carbureters in the manufacture of gas.

In the manufacture of water gas the process is divided into two periods, 1st, the blow, during which period the temperature or heat 15 in the carbureter is raised sufficiently to cause a vaporization of the oil and a disintegration of steam, and 2nd, the run during which period the steam and oil are admitted to the carbureter and the generation of gas 20 takes place. These two periods are alternate at definite intervals.

The present invention has particular reference to the devices for mechanically feeding the oil.

25 Heretofore variation in the feeding of steam and oil to the heated carbureter has been effected by hand, and has been largely a matter of guess work or mere judgment on the part of the operator who gradually cuts 30 off the oil and steam supply as the temperature in the carbureter lowers during the run period. The result is a more or less waste of oil and an ununiform product. The desideratum is a mechanical oil-feeding device which 35 at the beginning of the run period will admit or feed oil to the carbureter with maximum rapidity, and which, as the temperature in the carbureter gradually lowers during the run, will correspondingly gradually reduce 40 the quantity of oil admitted until the completion of the run. In this way only as much oil will be admitted to the carbureter as can be properly vaporized and converted into gas.

45 In order to economically reduce the quantity of oil that is being fed but at the same time to supply as much as the temperature and heat conditions in the carbureter will convert, I have provided a device that upon 50 being started will then automatically vary and reduce the quantity of oil from the beginning to the end of the run period, which results in a considerable saving in the quan-

55 tity of oil used and in producing a uniform quality of gas.

With these and other objects in view, the invention is illustrated in the accompanying drawings, in which,

Figure 1, shows a diagrammatic view of a portion of the oil supply system. Fig. 2, 60 illustrates a side elevation of the cut-off valve and its operating devices. Fig. 3, illustrates on a larger scale a longitudinal section through the oil-feed valve. Fig. 4, shows a plan view of the oil and steam supply pipes; 65 the valves controlling the same and the reciprocating lever devices for operating said valves. Fig. 5, shows a detail sectional view through the needle valve,—the section being taken on the line 5—5 of Fig. 3, and Figs. 6 70 and 7 illustrate a side elevation and plan view respectively of the connection between the rack bar and the rod that connects it with the valve stem.

75 While the present invention has particular reference to the mechanically operated oil-feed cut-off valve, I prefer to show the same in connection with a portion of a suitable oil-feed system.

By reference to Fig. 1 of the drawing it 80 will be understood that the oil from a suitable source of supply or storage is forced by a pump, 1, of any suitable construction through a meter, 2, and from the latter to an oil heater, 3, which is interposed between the 85 meter and the cut-off valve mechanism, and the latter is interposed between the oil heater, 3, and the carbureter, 5. The said cut-off valve mechanism is supported by a suitable base, 4; a housing, 6, is mounted on the base, 90 and a valve casing, 7, having a suitable bracket, 8, is supported in a horizontal position on top of the housing. By reference to Fig. 3 it will be seen that the casing is provided with an interior valve chamber, 9, into 95 which an oil-inlet pipe, 10, enters, and also has a tapered valve-seat, 11, at one end beyond the inlet pipe. At the other end the casing is provided with a stuffing box, 12, which may be of any desired or well known construction. A valve, 13, of the needle type having a tapered or conical end, 14, has its large end fitted snugly in the casing so as to move longitudinally therein and the point end, 15, when the valve is in the retracted or wide-open position, has position in or adja-

cent to the largest part of the tapered valve seat, 11. A stem, 16, passes through the stuffing box, 12, and has its inner end connected in any suitable manner to the valve; 5 the stuffing box maintains a tight joint around the stem. The outer end of the valve stem is provided with a circular head, 17, with an annular groove, 18, extending circumferentially around and adjacent said head, for a purpose presently to be described.

10 A bracket, 19, is secured to the housing, 6, and extends horizontally from one side thereof and a bracket bearing, 20, rests upon the bracket, 19, and is provided with a horizontal bearing, 21, and a vertical bearing, 22. A horizontal driving shaft, 23, extends through the bearing 21, and carries a pinion, 24, at its outer end while the inner end of said shaft enters the housing, 6, and is driven by any 15 suitable power contained in said housing. In the present instance I contemplate employing an electric motor to drive the horizontal shaft, and have shown the electrical switch, 27, on the exterior of the housing for this purpose, it being deemed unnecessary to 20 illustrate the motor in detail. At the outer end the bracket, 19, is provided with a step bearing, 28, in which the lower end of a vertical shaft, 29, rests. This vertical shaft carries a bevel gear, 30, which meshes with and is driven by the pinion, 24, on the horizontal driving shaft, 23. The upper end of the vertical shaft, 29, carries a pinion, 31, which meshes with and drives a gear, 32, on a horizontal shaft, 33, which latter is sustained in bearings, 25, at the upper side of the bracket, 20.

25 The valve, 13, is to be moved longitudinally in the chamber, 9, through the operation of the valve-stem, 16, and in order to effect this operation, I provide a movable rack-bar, 34, having teeth at its lower side, and this rack-bar is pivotally connected to a rod, 38, which latter is provided with a central longitudinal slot, 35, into which a central tongue, 36, on the rack bar, 34, projects,—the two parts being pivotally connected by means of a horizontal pivot pin, 37. The rod, 38, to one end of which the rack bar is pivotally 30 connected has its other end connected with the valve stem, 16, by means of a two-part sectional coupling, 40, which latter has a slotted recess, 41, that receives the head, 17, on the end of the valve stem. A hard metal 35 plate, 42, is fitted in the recess of the coupling and is provided with a central cavity in which a ball, 43, is placed so as to have bearing therein, and said ball also has bearing in a similar cavity in the head, 17, and thus 40 there is provided an anti-friction thrust bearing between the coupling and valve-stem. A collar, 44, encircles the slotted portion of the sectional coupling to hold the head, 17, in place in the coupling recess.

45 In order to support the rack-bar and the

valve-stem I provide on top of the bracket, 20, a bearing, 45, through which the rack-bar and rod, 38, slides when moved longitudinally, and a pinion, 46, is carried on a horizontal shaft, 33, and meshes with the teeth 70 of the rack-bar to move the latter. A hand grasp, 47, is provided on the outer end of the rack-bar by means of which said bar may be drawn backwardly by the operator, as will presently be explained.

75 From the foregoing description it will be seen that as the driving shaft, 23, revolves it will operate the vertical shaft, 29, and also the horizontal shaft, 33. This revolution of the horizontal shaft will cause the rack-bar 80 to move longitudinally and thus drive the stem, 16, and valve, 13, through the valve-chamber, 9, so as to effect a gradual closing of the port, 48, at the oil-outlet end of the chamber, 9. During this inward closing 85 movement of the valve I prefer to impart a rotation to the needle valve, 13, in order that the latter may grind its way through the chamber and effect a tight closure against the seat, 11, by slightly rotating as it contacts with said seat. To accomplish this rotation of the valve I provide the latter with a spiral groove, 49, which extends circumferentially around the valve and in a longitudinal direction and a stationary pin, 50, is rigidly secured in the wall of the valve casing, 7, and projects into the said spiral groove so that as the valve is moved longitudinally it will also turn. The turning of the valve with respect to the coupling, 40, is facilitated by the interposition of the anti-friction ball, 43.

90 By the construction herein described the quantity of oil admitted to the carburetor will automatically be gradually reduced from the beginning to the end of the run period after the valve has been moved to the wide open position, but in addition to this general reduction in the quantity of oil, it is desirable that at the end of each run the steam and oil shall both be entirely cut off. The mechanism for accomplishing this will now 95 be described.

100 A bracket, 51, projects above the valve casing and forms a support for a horizontal bar, 52. One end of this bar is sustained or rests in a trip arm, 53, which is carried on and moves with the valve stem, 16, and collars, 54, and, 55, are provided on the horizontal bar, 52, at opposite sides of the trip arm. A suitable valve, 56, is provided in the oil pipe between the supply and the valve chamber, 9, and the stem, 57, of this valve extends entirely through the valve casing and carries an operating arm, 58, at one end while to the other end of said stem there is attached an arm, 59, carrying a weight, 60. A link-bar 61, has one end pivotally connected to the forward end of the horizontal bar, 52, so as to swing in a 110

vertical plane while the other end of said link-bar is pivotally connected by means of a pin, 63, to the end of the operating arm, 58. It will thus be seen that as the link-bar is moved longitudinally toward the oil valve the operating arm, 58, will swing and close the valve and thus cut off the supply of oil from the valve chamber. In a similar manner the steam is cut off by valve, 64, which is also provided with an operating arm, 65, and a weighted arm, 66. The link-bar, 67, that connects the arm, 65, with the bar, 52, extends along the rear of the oil valve and is pivotally connected to the bar, 52, at the opposite side from the link-bar, 61, of the oil-valve. When the oil and steam valves are open the cut-off needle-valve must also be open, and the steam and oil will pass through the pipe, 68, to the injector, 69, which discharges it into the carbureter, 5. During the blow period the oil and steam valves are closed and it is desirable, for the sake of economy, to automatically shutdown the motor so that as long as the valves are closed the motor will remain at rest, but will immediately and automatically start up again upon the opening of the valves. To effect this I provide a switch, 70, in the circuit of the motor, said switch being of the ordinary knife-blade type, and an operating bar, 71, is attached to and travels with the trip arm, 53, on the valve-stem. Collars, 72, and, 73, are provided on the operating bar, 71, at opposite sides of the switch handle, 74, so that when the valve-stem reaches the limit of the inner stroke the collar, 72, will contact with the switch-handle and break the circuit, thereby bringing the motor to rest. Upon a reversal or return of the valve-stem the collar, 73, will move the switch-handle, 74, to again effect a completion of the circuit and the motor will make another run.

In the operation of the device the heat in the carbureter is first raised in any suitable manner to the required or preferred temperature. During this period the needle-valve, 13, and oil and steam valves, 56, and, 64, are closed so that oil and steam cannot pass to the carbureter. When the heat in the carbureter reaches the desired temperature the operator grasps the handle, 47, of the rack-bar, 34, and raises the free end of said bar so as to disengage the teeth from the pinion, 46, and after thus disengaging said rack-bar the operator draws the latter bar rearwardly so as to fully open the needle-valve and also the oil and steam valves. When these valves are opened wide the rack-bar is then lowered to again engage the pinion, 46, and at this moment the greatest quantity of oil and steam will be admitted to the heated carbureter and immediately thereafter the rack-bar, 34, will be mechanically, gradually and continuously moved forward by the

pinion, 46, so as to effect a gradual closing of the needle valve. This closing of the needle valve is effected by a continuous movement of said valve from the wide-open to the entire cut-off position and there is no intermittent movement during the closing of the valve. In the preliminary portion of the stroke the needle valve alone operates but toward the final portion it effects the closing of the steam valve, 64, and the oil inlet valve, 56. This final portion of the stroke of the needle valve also causes an actuation of the switch, 74, so as to cut-out the motor at the end of the run and throughout the blow period, so that during the blow period the motor may be at rest. It will thus be seen that the valve operates so as to admit oil into the heated carbureter and to continuously vary or to reduce the quantity of oil as the temperature in the carbureter falls so that the variation in the quantity of oil is mechanically effected from the beginning of the run period.

Having thus described my invention what I claim is,—

1. A gas apparatus comprising a carbureter, an oil-supply, a steam-supply, valves controlling said supplies, a valve for gradually reducing the quantity of oil supplied to the carbureter, and means whereby each time the valves are opened said means will gradually close the same.

2. A gas apparatus comprising a carbureter, an oil-supply, a valve casing interposed between the carbureter and oil-supply, a needle valve operating longitudinally in said casing, and means whereby each time the needle valve is opened to admit oil said means will automatically operate the valve to gradually vary the quantity of oil supplied to the carbureter.

3. A gas apparatus comprising a carbureter; an oil-supply, a valve for controlling said supply, means for moving said valve and means whereby the movement of the valve will cause the valve moving means to be brought to rest.

4. A gas apparatus comprising a carbureter, an oil-supply, a valve for controlling said supply, a power mechanism for gradually closing the valve, and means operated by the movement of the valve to stop the power mechanism when the valve is closed.

5. A gas apparatus comprising a carbureter, an oil-supply, a valve for controlling said supply, a power mechanism for operating the valve, means operated by the movement of the valve in one direction to start the power mechanism and means operated by the movement of the valve in the other direction to stop the power mechanism.

6. A gas apparatus comprising a carbureter, an oil-supply, a valve casing, a needle-valve in said casing, a rack-bar for operating the needle-valve and means for operating the

rack bar whereby to continuously move the needle valve to effect a gradual reduction in the quantity of oil supplied.

7. A gas apparatus comprising a carbureter, an oil-supply, a valve casing, a needle-valve in said casing and having a stem, means for gradually moving the stem and valve toward the cut-off position, a steam valve, and means coacting between the stem 10 of the needle valve and the steam valve whereby to operate the latter.

8. A gas apparatus comprising a carbureter, an oil-supply, a valve casing, a needle valve having a stem, a rack for operating the 15 needle valve, motor mechanism for operating the rack, a circuit breaker, and means coacting between the circuit and one of said movable parts to stop the motor when the valve has cut off the supply of oil.

20 9. A gas apparatus comprising a carbureter, an oil supply, a needle valve interposed

between the carbureter and oil supply, means whereby the valve may be moved in one direction to open the same and means for gradually closing the valve by moving it 25 in the opposite direction at a predetermined rate.

10. A gas apparatus comprising a carbureter, an oil supply, a needle valve between the carbureter and oil supply, means whereby 30 the valve may be moved in one direction to open the same, means for operating the valve in a reverse direction to close it at a predetermined rate, and means for rotating the valve as it is moving to the closed position. 35

In testimony whereof I affix my signature in presence of two witnesses.

FREDERICK H. WAGNER.
